DAVID McMASTER, OF SEATTLE, WASHINGTON.

MACHINE FOR APPLYING PLASTER.

Application filed April 10, 1926. Serial No. 101,091.

My invention relates to improvements in plastering machines and the object of my invention is to provide a machine of simple and efficient construction that will put plaster on a wall faster and cheaper than it can be put on by hand.

Another object is to provide a plastering machine that will permit the plaster to be applied entirely up to and into the corners 10 formed by intersecting walls and ceilings.

A further object is to provide a plastering machine which applies the plaster or mortar to the wall in substantially the same manner as it is applied by an ordinary plasterer's trowel, thus insuring a proper clinching 15 of the plaster and thereby insuring permanence and durability of the work.

A further object is to provide a portable plastering machine having means for accurately and evenly finishing the surface of 20 the work.

Other and more specific objects will be apparent from the following description taken in connection with the accompanying drawings.

In the drawings Figure 1 is a view in vertical mid-section of a plastering machine constructed in accordance with my invention parts being shown in elevation.

Fig. 2 is a view in front elevation of the same.

Fig. 3 is a view in cross section substantially on broken line 3—3 of Fig. 1.

Fig. 4 is an enlarged fragmentary view 35 in elevation of a detail of the invention.

Fig. 5 is a fragmentary sectional view of the machine showing the mortar box or hopper at the uppermost limit of its movement and illustrating the manner of applying the plaster to that portion of a wall adjacent 40 an intersecting ceiling.

Figs. 6 and 7 are perspective views of the mortar box or hopper and the movable partition for the same respectively.

Referring to the drawings, throughout 45 which like reference numerals designate like parts, I show an upright frame composed of four posts 8, arranged in rectangle formation and rigidly secured together at their bottom ends by suitable cross members 9. The upper portion of the frame is preferably formed of four channel bars 10, of smaller size than the channel bars forming the posts 8 and telescopically disposed within 50 said posts 8, to thereby constitute an extensible frame that may be adjusted as to

height. The posts 10 are secured together at their top ends by cross bars 11 and said posts 10 are adjustably secured to the posts 8 by suitable bolts 12.

The upright frame formed by posts 8 and 60 10 is mounted on suitable wheels 13, so that it may be easily and conveniently moved.

The two wheels 13 at the front side of 65 said frame are arranged in alignment so that they may be caused to move along a cleat or straight edge 14 that is placed on the floor on which the machine is supported, adjacent to a wall to which plaster is to be applied.

Mounted for vertical movement at the 70 front of the machine is a mortar box or hopper, comprising a bottom 15, and two upright end members 16. The rear edges of the end members 16 are arranged to rest 75 against and be guided by the front frame members 8. The hopper bottom 15 extends rearward beyond the front frame members 8, as shown in Figs. 1, 3 and 6, forming a platform 17 which platform is notched as 80 at 18 to fit over the front frame members.

A downwardly extending plate 20, hereinafter termed a trowel member, is hinged by pivot member 21 to the front edge of the hopper bottom 15, and extends downwardly from said hopper bottom 15 at an angle inclined slightly forward from the vertical. The trowel member 20 is supported at each end by slotted strap members 22, adjustably held by bolts 22, so that the 90 angle of inclination of said trowel may be varied relative to a wall upon which it is operating.

A partition member 23 is slidably disposed within the hopper and constitutes a 95 movable rear wall for the same, said partition member serving to force mortar which may be placed in the hopper outwardly over the trowel member 20 when it is moved forwardly. Angular braces 24 are secured to the rear side of the partition 23 and arranged to rest upon the platform 17 and be guided by cleats 25 on said platform, for guiding and supporting said partition 23.

A feed screw 26 is secured to the center of the partition 23 on the rear side and extends rearwardly therefrom. A pinion 27 is threaded on to the feed screw 26 and is arranged to mesh with a vertical gear-rack 110 28, so that as the hopper, together with feed screw 26 and pinion 27, is moved ver-

tically, the pinion 27 will be rotated and will move the partition 23 forwardly or rearwardly within the hopper.

The rack bar 28 is supported and reinforced by a vertically arranged channel member 30 that rests against the rear edge of the same. A U-shaped bracket 31 extends around channel member 30 and rack bar 28 and forms a bearing for the hub portion of the pinion 27, through which the feed screw passes, so that said pinion will always be held fully in mesh with the rack bar 28. A roller 32 may be provided in the outer end of the bracket 31 to relieve the thrust against the pinion 27.

An angular bracket 33 is rigidly secured to the rear end of platform 17, so as to extend upwardly and forwardly therefrom and said bracket 33 has a roller 34 in its upper end that is arranged to roll upon the vertical channel bar 30 as the hopper is moved up and down.

A hole 35 is necessarily provided in platform 17 to permit the rack bar 28 and channel member 30 to pass through said platform. The channel member 30 is rigidly secured to the frame of the machine at the bottom and a section 36 of the rack bar 28 at the bottom end is removably secured to said channel member 30 so that it may be detached to permit the pinion 27 to be turned by hand on feed screw 36 to properly position the partition member 23 in the hopper for walls of different heights as hereinafter explained. To provide adjustment as to height at the upper ends of the rack member 28 and channel 30, I preferably provide with each machine a plurality of sections of said rack bar and channel member, each of different length to correspond to different standard heights of ceilings, said rack bar and channel member sections preferably having dowel connections with the main sections of said channels and rack bar, as indicated at 37.

The hopper and parts connected therewith are supported for vertical movement by three cables 40, 41, and 42, arranged respectively at the two sides just in front of the frame members 8, and near the middle at the rear end of the platform 17. These cables pass upwardly over rollers 43 and 44, thence downwardly and are wound upon drums 45 on a transverse shaft 46 that is mounted on the rear frame members 8. The ends of the transverse shaft 46 are preferably squared so that a crank arm 47 may be applied to either end to turn said shaft and raise or lower the hopper. The ends of shaft 46 are necessarily within the limits of the width of the frame so that said frame may be moved closely against a wall.

A finishing member or straight edge 50 is arranged to be detachably secured to either end of the front frame members 8 so that it may

be drawn over plaster that has just been applied by moving the machine sidewise, to thereby finish the surface of said plaster. The straight edge 50 extends continuously from the floor to the ceiling of the room that is being plastered and a plurality of said straight edges of different lengths may be furnished with the machine to accommodate different heights of ceilings. Suitable ratchet means 49 may be provided for selectively locking the shaft 46 against rotation in either direction.

To prevent mortar from being forced out at the sides of the hopper along the front edges, I provide adjustable end plates 51 that are adjustably secured to the ends 16 by slot and bolt means 52 and are arranged to be moved forwardly in close proximity to a wall. The plates 51 may be adjusted to compensate for adjustments in the angularity of the trowel member 20.

In the operation of this plastering machine, the machine is placed in front of a wall 53 which is lathed or otherwise properly prepared for the reception of plaster. A guide member 14 to guide the machine for movement across the floor parallel to the wall is secured to the floor 54 on which the machine rests in such a manner as to form a straight trackway parallel to, and at the proper distance from the wall so that the front pair of wheels 13 that support the machine may press against, and be moved along, said guide member, thus keeping the machine always at a constant distance from the wall.

The machine is set up at the location where the first strip or swath of plaster is to be applied, usually in a corner of the room, with the lower edge of the trowel member 20 at the proper distance from the wall to apply a coat of plaster of the desired thickness. The partition plate 23 is positioned by adjusting the pinion 27 on the feed screw 26 so that said partition plate will be moved inwardly to a position distant from the wall 53, substantially the thickness of the coat of plaster that is being applied in moving the hopper from the lowermost position, Fig. 1, to the uppermost position, Fig. 5. This may be set by trial by raising and lowering the hopper, but can ordinarily be set by gauge or measurement for walls where the ceiling is of standard height. The hopper, in its lowermost position, Fig. 1, is then filled preferably level full of mortar, the side plates 51 having been adjusted into close proximity to the wall 53. The hopper is then raised by turning the shaft 46 and as it moves upward the pinion 27, meshing with rack 28 moves partition member 23 forward, forcing mortar outward over the upwardly moving trowel member 20 which operates in the same manner as an ordinary plasterer's trowel to rub such mortar onto

the wall and to cause it to pass between the lath or equivalent means and clinch properly on the rear side. In this manner the machine applies a strip or swath of plaster the width of the trowel member as it moves up along the wall. The movement of the partition member 23 is gauged so that when the top of the hopper strikes against the ceiling 55, Fig. 5, the front surface of the partition member will be in substantially the plane of the finished wall or a distance equal to the thickness of the coat of plaster from the front sides of the lath and the mortar trapped between said partition and the wall will be forced against the lath and squeezed between said lath and properly clinched, thus finishing the swath of plaster entirely to the ceiling. While the hopper is thus held in its uppermost position the straight edge or finishing member 50 is adjusted into the correct position and the entire machine is moved sidewise drawing the partition member 23 sidewise across the plaster that is held between said partition member and the wall and then drawing the straight edge 50 sidewise across the entire newly applied swath of plaster giving the same a true and even finish. In working in a corner the straight edge 50 is necessarily removed while the first swath of plaster is being applied and is put on and adjusted to the wall after the machine has been moved outwardly a short distance from the wall. The straight edge 50 is reversible and may be placed on either side of the machine. Different finishes may be secured on the plaster surface by varying the angle of the trowel 20 and straightedge 50.

In outside plaster work, as in applying stucco finish, and in inside work where ceilings do not interfere, the trowel member may be allowed to move entirely to the top of the work that is being applied. Obviously this can not be done in inside work where there are ceilings and the means for applying the plaster adjacent to the ceiling constitutes an important part of my invention.

The frame is rigid and substantial and will ordinarily withstand any back thrust that may be applied thereto by the trowel 20 and associated parts without yielding. If necessary when the frame is extended a brace member may be attached to the upper position of the frame members 8 so as to extend rearward and downward to a suitable rigid footing.

The angle brace 33 serves to brace the hopper for vertical movement along the frame.

The machine is strong and simple in construction, reliable and efficient in operation, not liable to get out of order, can be operated by one man, and is capable of applying plaster very much faster than it can be applied by one man by hand.

The foregoing description and accompanying drawings clearly disclose a preferred embodiment of my invention but it will be understood that this disclosure is merely illustrative and that numerous changes in the machine may be resorted to within the scope and spirit of the following claims.

I claim:

1. In a plastering machine, a hopper, a trowel member at one side of said hopper and external to said hopper and pivotally and adjustably connected with one edge of said hopper, and means for feeding mortar from said hopper outwardly over said trowel member. 75

2. In a plastering machine, a frame, a hopper movable on said frame, a trowel member at one edge of said hopper, said trowel member being entirely on the exterior of said hopper and being pivotally connected with the edge of the hopper, means for adjusting the angular position of said trowel member, and means for feeding mortar from said hopper outwardly over said trowel member. 85

3. In a plastering machine, a frame, a hopper movable on said frame, a trowel member pivotally connected with one edge of said hopper and extending outwardly therefrom at substantially right angles to the adjacent side of the hopper, means for rigidly supporting said trowel member in various adjusted angular positions and a movable partition in said hopper for forcing mortar outwardly over said trowel. 95

4. In a plastering machine a hopper arranged to be guided for movement along a wall the side of said hopper adjacent the wall being open in close proximity to the wall, an inclined trowel member adjustably connected with one edge of said hopper, and arranged to be adjusted into different angular positions, side plates adjustably connected with the edges of said hopper at each end of said trowel member, and means for feeding mortar from said hopper outwardly over said trowel member. 105

5. In a plastering machine a frame, a hopper movable along said frame, said hopper being open at one side and being adapted to be positioned with its open side adjacent a wall that is to be plastered, a trowel member arranged to extend along said wall in close proximity thereto and at a comparatively slight angle relative to the plane of the wall; said trowel member being entirely outside of said hopper and pivotally connected with one edge of the open side of said hopper, means for adjusting the angular position of said trowel member and a partition in said hopper arranged to be moved automatically to force mortar outwardly from the open side of said hopper against the wall. 120

6. In a plastering machine, a frame, a hop- 130

per movable on said frame, a trowel member connected with one edge of said hopper, a partition member movable within said hopper and means operated by movement of said hopper, for moving said partition member within said hopper when said hopper is moved on said frame to force mortar outwardly over said trowel member.

7. In a plastering machine, a movable hopper and a trowel member adjustably connected with one edge of said hopper and arranged to be set at different angles relative to the plane of a wall along which said trowel member is movable.

8. In a plastering machine, a frame, a vertically movable hopper, open at the forward end, side plates adjustably secured to the side edges of said hopper and movable toward and away from a wall to which plaster is being applied, a trowel member secured to the forward edge of the bottom of said hopper and extending downwardly and forwardly therefrom, the front end of said hopper being open, a movable partition forming the rear wall of said hopper and means for moving said partition forwardly as said hopper is moved upwardly.

9. In a plastering machine, an upright frame arranged to be supported adjacent a wall, a hopper guided for vertical movement on said frame, said hopper being open at the front, a trowel member hinged to the bottom of said hopper at the front edge, and extending downwardly therefrom, means for supporting said trowel member in adjusted angular positions, a partition forming a movable rear wall for said hopper, a feed screw connected with said partition, and means operated by the vertical movement of said hopper for moving said feed screw and said partition.

10. In a plastering machine, an upright frame arranged to be supported adjacent a wall, a hopper guided for vertical movement on said frame, said hopper being open at the front, a trowel member hinged to the bottom of said hopper at the front edge and extending downwardly therefrom, means for supporting said trowel member in adjusted

angular positions, a partition forming a movable rear wall for said hopper, a feed screw connected with said partition, a pinion having a hub threaded onto said feed screw, a vertical rack, means for holding said pinion in mesh with said rack, and cable operated hoisting means for raising and lowering said hopper.

11. In a plastering machine of the class described, an upright frame, wheels supporting said frame for movement over a floor, certain of said wheels being adapted to follow horizontal guides, a hopper arranged for vertical movement at the front of said frame, the front of said hopper being open, and the bottom of said hopper extending rearwardly beyond the side walls of the same, a trowel member extending downwardly at a slight forward incline from the front edge of the bottom of said hopper and arranged to have mortar discharge thereover, a partition member forming a movable rear wall for said hopper, brace means on the rear side of said partition member slidably guided on the rearwardly protruding bottom of said hopper, means for raising and lowering said hopper and means for imparting movement to said partition member in a predetermined ratio to the movement of said hopper.

12. In a plastering machine, an upright portable frame, means for guiding said frame for sidewise movement parallel to and in close proximity to a wall, means carried by said frame for depositing mortar on a wall and a removable straight edge carried by said frame for smoothing mortar on said wall when said frame is moved sidewise.

13. In a plastering machine an upright portable frame arranged to be guided for sidewise movement parallel to a wall means carried by said frame for depositing mortar on said wall, and means carried by one side of said frame for smoothing said mortar when said frame is moved sidewise.

The foregoing specification signed at Seattle, Washington, this 31st day of Mar. 1926.

DAVID McMASTER.
